UNITED STATES PATENT OFFICE.

JOHN OBLENIS, OF MENTONE, INDIANA.

SAND-BAND FOR VEHICLES.

SPECIFICATION forming part of Letters Patent No. 640,219, dated January 2, 1900.

Application filed September 11, 1899. Serial No. 730,136. (No model.)

To all whom it may concern:

Be it known that I, JOHN OBLENIS, a citizen of the United States, residing at Mentone, in the county of Kosciusko and State of Indiana, 5 have invented a new and useful Sand-Band for Vehicles, of which the following is a specification.

My invention relates to a novel sand-band designed to protect the bearing-faces of an 10 axle skein and hub from sand or other gritty particles which would tend to create friction.

The object of my invention is to produce a device of this character adapted by reason of its peculiar construction to be quickly applied 15 to or removed from axles of different sizes and to constitute a closed casing, which will prevent foreign substances from coming into contact with the wearing-surfaces.

To the accomplishment of these and other 20 objects subordinate thereto my invention consists in the novel construction and arrangement of parts hereinafter described, illustrated in the accompanying drawings, and succinctly pointed out in the appended claims.

25 Referring to said drawings, Figure 1 is a sectional view through a hub and my device, illustrating the application of the latter and showing an axle-skein in elevation. Fig. 2 is a perspective view of the sand-band de- 30 tached. Fig. 3 is a similar view of the hub-band. Fig. 4 is a rear elevation of the subject-matter of Fig. 2.

Referring to the numerals of reference designating corresponding parts in the several 35 views, 1 indicates an axle-skein, 2 its flange, and 3 a wheel-hub revolvably mounted upon the skein and secured in place, as usual, by the skein-nut 4.

5 indicates the hub-band, secured at the 40 rear face of the hub 3 and extending into the sand-band 6, carried by the sheath 7 of the skein or by the axle, as the case may be, immediately in the rear of the flange 2.

The interfitting relation of the hub and 45 sand bands is designed to prevent sand or the like from working between the flange 2 and the end of the hub to the contacting faces of the spindle and hub-lining.

This class of devices is adapted for attach- 50 ment to vehicles and is particularly useful after the wearing-surfaces have separated to some extent by use. It is therefore desirable

to construct the band in a manner to facilitate its attachment to parts of varying sizes.

The sand-band 6 is constructed of metal 55 and is composed of two adjustable and detachable sections 8 and 9, each of which comprises a pair of hinged segments 10 and 11 and 12 and 13. When these sections are drawn together—as, for instance, when the 60 band is clamped upon the axle or skein sheath—the outer contour of the band is practically circular and the inner contour is slightly oval in conformity to the usual oval contour of the axle or sheath behind the skein- 65 flange. Each of the several segments of the band is composed of a segmental bottom plate 14 and inner and outer segmental flanges 15 and 16, extending in the same direction, but of different widths—that is to say, the outer 70 annular flange of the band, composed of the several flanges 16, extends from the bottom plate into contiguity with the rear or inner end of the hub, while the inner flange is only sufficiently wide to extend into comparatively 75 close proximity to the rear side of the skein-flange 2.

The bottom plates 14 are provided at their inner edges with gripping-teeth 17, which extend inwardly beyond the inner flange 15 and 80 are designed to bite into the axle or skein, as the case may be, when the sand-band is clamped thereon in the manner to be described.

The general form and arrangement of the 85 sand-band being understood, I will now proceed to a description of the hinge connections between the segments of the sections, and of the adjustable connections between the opposed ends of the sections, and also of the 90 means employed for protecting the joints, for limiting the relative movement of the hinged segments, and for yieldingly urging said segments in a direction to grip the axle.

The contiguous ends of the bottom plates 14 95 of the segments are respectively formed with concave and convex curvatures 18 and 19, which terminate in the contacting faces of stop-lugs 20, projecting inwardly from the segments, and a hinge is formed by passing a pintle 100 21 through the convexly-curved plate 14, concentric with the curvature, and through a superimposed hinge-lip 22, soldered or otherwise secured upon the opposed plate 14 and

projecting beyond its end. This construction is common to the hinge connection between the segments of both sections; but in addition to the hinge and stop mechanism thus formed I provide the upper section with means for urging the segments together. This mechanism consists in extending the outer flange of one segment considerably beyond the adjacent end of the opposed outer flange and in slightly curving the extended end beyond the pintle 21 in a manner to cause it to bear with a spring action upon the opposed flange when the segments are drawn apart—as, for instance, during the application of the device to an axle. The sections thus constructed are designed to be relatively adjusted by means of adjusting-bolts 23, passed through eyelets 24, projecting from the contiguous ends of the outer flanges of the sections and secured by nuts 25, the joints between the sections being closed by overlapping lips 26, soldered or otherwise secured upon the bottom plates of one section, and by similar lips 27, secured upon the faces of certain of the outer flanges.

The outer flange of the sand-band is cut away at the bottom of the latter to provide a grease-outlet 28, and, if desired, the several joints of the inner flange may be protected by overlapping lips similar to the lips 26 and 27.

The hub-band 5, designed to coöperate with the sand-band just described, comprises an annular band 29, provided at one edge with a series of prongs 30, which in practice are forced into the rear face of the hub, and at its opposite edge is formed an annular guard-ring 31, designed in practice to be located between the inner and outer annular flanges of the sand-band and in practically parallel relation with the bottom plate thereof, as illustrated in Fig. 1 of the drawings. Thus any sand or grit passing between the contiguous edges of the sand-band and hub will be deposited upon the hub-band and, being prevented by the guard-ring 31 from escaping farther toward the skien, will gravitate to the bottom of the sand-band and will be discharged with accumulated grease or lubricating-oil through the opening 28 in the outer flange of the band.

It will be observed that by reason of the hinge connection between the segments of the sections and by reason, further, of the adjustability of the sections with respect to each

other my device may be easily applied to 55 axles and hubs of various makes and sizes; but while the embodiment of my invention illustrated and described appears at this time to be preferable I do not limit myself to the structural features defined, but reserve the 60 right to change, modify, and vary the construction of the device within the scope of the protection prayed.

What I claim is—

1. A sand-band, comprising a plurality of 65 sections, each of the latter being formed by yieldingly-connected segments, and means for adjustably connecting the several sections.

2. A sand-band composed of a plurality of 70 sections, each of the latter comprising hinged segments and means for yieldingly opposing relative movement of the segments forming the respective sections.

3. A sand-band composed of a plurality of 75 adjustable sections, each comprising hinged segments, means for limiting the relative movement of the segments in one direction, and means for yieldingly resisting relative movement thereof in the opposite direction. 80

4. A sand-band composed of a plurality of sections, each comprising hinged segments, independent adjusting devices connecting the opposite ends of the sections, and means for protecting the joints between the 85 segments and sections.

5. A sand-band composed of a plurality of adjustable sections, each comprising hinged segments, inner and outer annular flanges substantially concentric and of different 90 widths, teeth extending inwardly beyond the inner flange, overlapping lips intermediate of the sections, eyelets projecting from the outer flanges at the contiguous ends of the sections, adjusting-bolts passed through the 95 eyelets, nuts carried thereby, stop-lugs carried by the segments, and a spring formed by extending the end of the outer flange of one segment into contact with the outer face of the opposed flange of the adjacent segment. 100

In testimony that I claim the foregoing as my own I have hereto affixed my signature in the presence of two witnesses.

JOHN OBLENIS.
